DESIGN FOR A FOOT BATH TRAY

Clarence L. Weirich, Westport, Conn., assignor to The C. B. Dolge Company, Westport, Conn.,
a corporation of Connecticut

Application December 15, 1937, Serial No. 73,643

Term of patent 14 years

To all whom it may concern:

Be it known that I, Clarence L. Weirich, a citizen of the United States, residing at Westport, in the county of Fairfield and State of Connecticut, have invented a new, original, and ornamental Design for a Foot Bath Tray, of which the following is a specification, reference being had to the accompanying drawing, forming a part thereof.

I claim:

The ornamental design for a foot bath tray as shown.

CLARENCE L. WEIRICH.
